UNITED STATES PATENT OFFICE.

EDWARD PAUL O'DONNELL, OF KIEFER, OKLAHOMA.

VALVE-GRINDING MACHINE.

Application filed September 9, 1927. Serial No. 218,587.

It is the purpose of the present invention to provide a machine whereby all of the valves of an internal combustion engine can be ground simultaneously, thereby making it possible to perform this operation with considerable saving in both time and labor.

One of the chief characteristics of the invention resides in the provision of means whereby the valves are rotated approximately one-half a turn in one direction, and then reversely rotated a quarter of a turn, with a view of more efficiently grinding the valves, with means for lifting the valves off their seats at predetermined intervals and subsequently reseating the valves in a different position.

Another object of the invention resides in providing a machine of the class in question, wherein the working parts are arranged within a suitable casing capable of being swung over the motor so that the valves can be ground from any angle.

The nature and advantages of the invention will be better understood when the following detailed description is read in connection with the accompanying drawings, the invention residing in the construction, combination and arrangement of parts as claimed.

In the drawings forming part of this application, like numerals of reference indicate similar parts in the several views, and wherein:

Figure 1 is a view partly in section, showing a machine arranged upon the motor for use.

Figure 2 is a fragmentary enlarged end elevation with parts broken away.

Figure 3 is a sectional view taken on the line 3—3 of Figure 1.

Figure 4 is a sectional view taken on the line 4—4 of Figure 1.

Figure 5 is an enlarged view of one of the tubular members, partly in section, and its associated parts.

Figure 6 is a detailed sectional view on line 6—6 of Figure 2.

Figure 7 is a similar sectional view on line 7—7 of Figure 1.

The machine forming the subject matter of the present invention essentially embodies a frame 10, the frame being of inverted U-shaped configuration and supporting spaced parallel shafts 11 and 12 respectively. The shaft 11 is mounted for rotation, while the

shaft 12 is mounted for sliding movement in suitable slots formed in the end members 13 of the frame.

For each valve of the motor, I provide a 60 grinding tool which embodies a hollow tubular member 14, the bottom of which is solid, as at 15, and provided with a transverse slot 16 to accommodate a valve engaging tool 17. By reason of the slot 16, it is manifest that 65 the tools of different characters can be inserted within the slot to accommodate different makes of valves, and each tool so used is held associated with the tubular member by means of a fastening screw 18 which is 70 carried by the solid bottom 15, as shown. Rising from the bottom 15 of each tubular member is a rod 19, arranged centrally of the member and projecting an appreciable distance above the top thereof. This rod, 75 from a point adjacent the top of the tubular member to the end of the rod, is of rectangular contour in cross section which is received in the squared bore on the stub shaft or hub of a beveled gear 20 in a manner 80 which allows the rod sliding movement with relation to the shaft 11, for a purpose to be hereinafter described. The shaft 12 is provided with a series of openings 21, through which the various rods 19 pass, and the gears 85 20 associated with these rods are arranged directly beneath the shaft 11. Mounted on this shaft 11 is a pair of spaced beveled gears for each gear 20, and the gears of each pair above mentioned are indicated at 23 90 and 24 respectively. These gears are constructed to alternately mesh with the gear 20 for the purpose of rotating the rod 19 in opposite directions at relatively different distances for the efficient grinding of the 95 valves. In other words, the gear 20 is provided with teeth 25 which extend about the gear a distance sufficient to rotate the rod 19 a half revolution in one direction when this gear meshes with the gear 20, and at which time the gear 24 is out of mesh with the gear 20, because of the fact that the teeth 26 on this gear only extend part way around the gear. Then again, the gears 23 and 24 are arranged upon the shaft 11 with their teeth diametrically opposed, so that the gears 23 and 24 are alternately brought into meshing engagement with the gear 20, which rotates the gear 20 in opposite directions and consequently causes the rod 19 to turn in 100 reverse directions. While the teeth 25 of the gear 23 rotate the rod 19 approximately one- 105 110

half of a turn, the teeth on the gear 24 are arranged to rotate the rod 19 in a reverse direction, but only approximately one-fourth of a turn in this direction. While the shaft 11 may be rotated in any suitable manner, I preferably make use of a small electric motor 27 mounted upon the frame 10, and including a sprocket 28 carried by the shaft of the motor. The shaft 11 extends an appreciable distance beyond one end of the frame and supports spaced sprocket wheels 29 and 30 respectively. A sprocket chain 31 is trained over the sprocket 28 of the motor and over the sprocket 29 on the shaft 11 whereby the latter is rotated, as will be readily understood. Projecting from the same end of the frame 10 and mounted for rotation is a stub shaft 32 which supports a cam 33 and a sprocket 34. Trained over the sprocket 30 carried by the shaft 11 and the sprocket 34 just mentioned, is a sprocket chain 35 by means of which the shaft 32 is rotated from the shaft 11. The cam 33 contacts a roll 36 carried by the shaft 12, and for each rotation of the shaft 32, the cam 33 cooperates with the roll 36 to lift the shaft 12 in the slots formed in the end members of the frame 10. The rods 19 are provided with collars 37 arranged with relation to one shaft 12, so that when the shaft 12 is lifted in the manner just described, it contacts the collars 37 and thereby lifts the tubular members 14 away from the motor.

During this operation, the valves are simultaneously lifted from their seats, and slightly turned so that when the tubular members are lowered, the valves will be re-seated in a different position, a fact coupled with the fact that the rods are rotated in reverse directions relatively different degrees, assures an efficient grinding of the valves. For the purpose of lifting the valves off the seats, I convert the tubular members 14 into magnets which, of course, attract the valves and lift them away from their seats, incident to the movement of the tubular members away from the motor. For this purpose, current is taken from the motor 27 to a transformer 38 and conveyed to a winding 39 about each rod 19. These windings 39 are wholly arranged within the tubular members 14, and connected with the solid bottoms 15 to magnetize the latter for the purpose of lifting the valves in the manner and for the purpose stated. If desired,

the valve refacing device 40 can be arranged upon the top of the frame.

This machine is mounted within a casing 41 preferably supported by legs 42, the casing being constructed to be swung upon hinges or pivots 43, so that the machine can be dropped down over a motor, or swung from any angle into a position for use, especially when used with a motor of the V-type. It is manifest that I have devised a machine for the purpose intended whereby all of the valves of the motor can be quickly and economically ground, and the work accomplished in comparatively quick order.

While it is believed that from the foregoing description, the nature and advantages of the invention will be readily apparent, I desire to have it understood that I do not limit myself to what is herein shown and described, and that such changes may be resorted to when desired as fall within the scope of what is claimed.

Having thus described the invention, I claim:

A means for grinding valves in an engine block, comprising a substantially U-shaped frame which is removably bolted on the block, valve engaging tools designed to each engage with a valve, a rod associated with each tool having an upper squared end, beveled gears having hub portions journaled on the frame having squared bores to receive the squared ends of the rods therein, oppositely disposed mutilated gears engaging each of the beveled gears, a shaft for the last mentioned gears, means for revolving the shaft whereby to cause the last mentioned gears to impart reverse motion to the first mentioned gears and to the rods associated therewith, guide means for the rods, comprising a reciprocating member mounted on the frame, rollers on the ends of said member, cams on the stub shafts mounted adjacent to and engageable with the first mentioned rollers, means for revolving the cams to elevate the guide means, means supporting the rods on the guide means for causing the same to be raised with the guide means and solenoids surrounding each rod and the tool engaging element thereon, and means for energizing the solenoids to attract the valves to raise the same from their seats.

In testimony whereof I affix my signature.

EDWARD PAUL O'DONNELL.
